UNITED STATES PATENT OFFICE.

FRANK W. COLLINS, OF ROCKLAND, MAINE.

PACKAGE FOR SHIPPING SHELL-FISH, &c.

SPECIFICATION forming part of Letters Patent No. 680,566, dated August 13, 1901.

Application filed December 5, 1900. Serial No. 38,719. (No model.)

To all whom it may concern:

Be it known that I, FRANK W. COLLINS, a citizen of the United States of America, and a resident of Rockland, Knox county, State of Maine, have invented certain new and useful Improvements in Packages for Shipping Shell-Fish, &c., of which the following is a specification.

My invention relates to a package or vessel for shipping lobsters and other shell-fish which require to be iced during transit, and it particularly relates to an improvement in the device patented to me in Letters Patent No. 653,567, dated July 10, 1900. In the patented device I found by experience that in the case of long shipments—for instance, where lobsters were sent from Maine to St. Louis during hot weather—a considerable portion of them had died for the lack of refrigeration in the center of the mass, and I have overcome this objection to my former shipping-package by means of the present invention, which consists in applying to said package a cylinder which extends from the diaphragm to the bottom, forming a continuation of the upper iced chamber, so that the melted ice and cold air from the upper iced chamber run down around the sides of the vessel and keep the outer lobsters cool and moist, and at the same time the ice which occupies the cylindrical chamber keeps the lobsters in the center cold and prevents them from dying. The lobsters are thus contained in a cylindrical chamber with a cold surface in the center and a cold chamber on top, and experience has shown that with this form of package they can be sent a long distance without dying in any considerable numbers, a very large proportion of them being kept alive several days in the hottest weather.

I illustrate my invention by means of the accompanying drawings, in which—

Figure 1 is a central vertical section through the package provided with my present improvement, and Fig. 2 is a horizontal section on the line $x-x$ of Fig. 1.

A represents a vessel which is formed tapering toward the bottom and flaring toward the top, with a cover B fastened on by suit-

able fastening means, as the bolts and nuts 50 a. About a third of the way down, as here shown, is a diaphragm C, fitting against the sides of the vessel and having its outer edges recessed to allow the drip and cold air to flow down along the walls of the vessel. Extending from the diaphragm to the bottom F of the vessel is a cylinder D, forming a cylindrical chamber, which forms a continuation of the iced chamber above the diaphragm. The cylinder D is preferably made from sheet 60 metal and is provided at its lower end with a flange d', which fits an annular groove in the bottom F; but it is also provided at a point near its top, immediately below the diaphragm C, with a bead d, which serves to assist in holding the diaphragm C in place. As the diaphragm and the bottom of the vessel are both constructed of a very light and thin material, the weight in the center of the diaphragm would sag the same downward, but 70 the bead upon the cylinder prevents this, and also if the cylinder were constructed without the flange upon its lower edge the cylinder would be forced through the bottom. For that reason I provide an annular groove in the bottom and the flange upon the cylinder. A drip-opening f is formed in the bottom F within the cylinder-chamber D.

In putting this package together the cylinder D is placed on the bottom, its flange fitting 80 in the corresponding recesses. The lobsters are then packed in the annular space, the diaphragm is inserted, and the ice is placed in the upper chamber and the cylinder.

It will be seen that in this package the lobsters may be easily re-iced when in transit without disturbing them.

I claim—

The herein-described package for shipping shell-fish, consisting of a downwardly-tapering vessel provided with an annular groove 90 in its bottom, a cover therefor, a horizontal diaphragm having a central opening and other openings adjacent to its outer edges, and a cylindrical chamber provided with a 95 bead near its top and a flange at the bottom, said flange being adapted to fit in the annular groove of the bottom of the vessel and the

bead to form a rest to support the diaphragm whose central opening surrounds the upper end of the tube; whereby the space above the diaphragm communicates with the interior of 5 the tube to form an ice-compartment and the space below the diaphragm and around the tube forms a storage-chamber.

Signed at Portland this 31st day of November, 1900.

FRANK W. COLLINS.
